UNITED STATES PATENT OFFICE.

JOHN R. CARTER, OF CINCINNATI, OHIO, ASSIGNOR TO ERNST H. HUENEFELD, OF SAME PLACE.

HEATING-STOVE.

SPECIFICATION forming part of Letters Patent No. 608,574, dated August 9, 1898.

Application filed March 7, 1898. Serial No. 672,979. (No model.)

To all whom it may concern:

Be it known that I, JOHN R. CARTER, a resident of Cincinnati, in the county of Hamilton and State of Ohio, have invented certain new 5 and useful Improvements in Heating-Stoves; and I do hereby declare the following to be a full, clear, and exact description of the invention, such as will enable others skilled in the 10 art to which it appertains to make and use the same.

My invention relates to an improvement in heating-stoves, the object being to provide a stove having a central fuel-feed, with down-draft-flues communicating with but located 15 outside of the fuel-feed collar, so as not to interfere with the feed of fuel.

A further object is to provide a stove with a series of hot-air-blast flues located around a central fuel-opening, so as to distribute 20 heated air over practically the entire bed of incandescent fuel, so as to insure uniform and practically complete combustion of the 25 gases generated.

With these objects in view my invention 30 consists in the parts and combinations of parts, as will be more fully explained, and pointed out in the claims.

In the accompanying drawings, Figure 1 is a view in vertical section, partly in elevation, 35 of a stove embodying my invention; and Fig. 2 is a detached view, partly in transverse section.

A represents a stove of any approved form and designed for burning either wood or coal. 35 When used for burning coal, the stove should be provided with a movable grate, but when used in a wood-burning stove, a closed fuel-pot similar to that disclosed in the James application, Serial No. 645,254, filed July 20, 1897, 40 should be used. I prefer, however, to provide the stove with a damper for supplying air at a point near the base of the fire-pot, and in coal-burning stoves this damper should be on a door conveniently located for the removal 45 of ashes. In either instance, however, the stove is provided at a point centrally over the fire-pot with an opening for the introduction of fuel, and within this opening and leading downwardly some distance below the

top of the fire-pot is the collar B. This collar is cylindrical in shape and is provided at its upper end with an outwardly-turned flange a, which latter rests on the top of the stove and supports the collar in its position within the fire-pot. This collar is provided at its lower end with an inwardly-turned flange b, forming a seat, on which rests the removable lid C, having a handle c. This lid closes the top of the fire-pot and prevents, to a large extent, the entrance of air at this point. Secured to the collar and communicating with openings in the collar are the air-blast pipes D, which latter are located in vertical planes outside of the collar, and hence leave the whole interior of the collar free and clear for the introduction of fuel. These pipes extend well down into the fire-pot, so as to discharge the air directly onto the burning fuel, and as there are preferably a plurality of hot-blast pipes employed it will be seen that the air drawn in is pretty well diffused over the entire body of burning fuel, thus mixing with the gases generated and promoting combustion, and as the pipes are subjected to the heat of the burning fuel the air is heated, and hence in proper condition for quick and thorough assimilation with the gases. The collar and fuel-opening may be covered with a register-plate or with a hood or cap having a damper therein.

In some stoves it might be desirable or advantageous to provide the stove with a fuel-door in front, and in such instance I would prefer to use three blast-pipes, one at each side and one at the back, leaving the front free for the admission of fuel. When it is desired to introduce fuel through the top opening of the stove or through the collar, the register plate, cap, or hood, or other part employed for closing the fuel-opening, and the lid C are removed, thus permitting the free and ready introduction of fuel without removing or interfering in the least with the blast-tubes. When the lid and register plate or cap are in place, air entering the latter is deflected by the lid and passes down to the burning mass through the blast-pipes.

While I prefer to employ a plurality of

pipes, still one might be considered sufficient. Hence I do not care to limit myself to any particular number.

It is evident that other changes might be made in the general form and arrangement of the several parts herein shown and described without departing from the spirit and scope of my invention, and hence I would have it understood that I do not limit myself to the precise details herein set forth, but consider myself at liberty to make such changes and alterations as fairly fall within the spirit and scope of my invention.

Having fully described my invention, what I claim as new, and desire to secure by Letters Patent, is—

1. The combination with a stove having a fuel-opening through its top, a removable hood for closing said fuel-opening and a collar seated within said opening, of a draft-pipe carried by said collar and projecting downwardly into the fire-pot, a removable lid lo-

cated within the collar and below the draft-opening therein and a damper above said draft-opening in the collar.

25

2. The combination with a stove having a fuel-opening through its top, a removable hood for closing said fuel-opening and a collar having an outwardly-turned flange at its upper end and an inwardly-turned flange at its lower end, the upper flange of said collar resting on the top of the stove, of a draft-flue outside the collar but secured to and depending from the same, a removable lid seated on the lower flange of the collar and a damper-plate closing the upper end of the collar.

In testimony whereof I have signed this specification in the presence of two subscribing witnesses.

JOHN R. CARTER.
